UNITED STATES PATENT OFFICE

WILLIAM H. BERGMANN, OF CLEVELAND, OHIO, ASSIGNOR TO THE AMERICAN FORK & HOE COMPANY, OF CLEVELAND, OHIO, A CORPORATION OF OHIO

D-TOP

Application filed September 16, 1929. Serial No. 392,911.

My invention relates to D-tops for implements and relates particularly to D-tops of the type adapted to be rigidly secured as a unit to the end of an implement shaft to securely support a hand grip between prongs of the D-top.

An object of my invention is to provide an improved metallic D-top for implements.

Another object of my invention is to provide an improved substantially tubular metallic D-top so constructed as to facilitate its ready manufacture in quantity production.

Another object of my invention is to provide an improved metallic D-top in two halves which of themselves are adapted to be interlocked for convenience in assembly and shipment pending the operation of affixing the halves to an implement.

Another object of my invention is to provide for the accomplishment of any of the foregoing objects in a metallic D-top which has a smooth exterior surface without sharp edges engageable by the hands of an operator of the tool to which the D-top has been applied.

Another object of my invention is to provide an improved D-top which will be sturdy and strong, resisting breakage and bending in use, and which may be formed from metallic blanks stamped from a sheet of metal in such a way that very little waste metal will be left in the sheet after successive of the stampings are blanked therefrom.

Another object of my invention is to provide an improved two-piece substantially tubular D-top construction, adapted to be secured together without requiring additional securing clamps, or the welding of the parts, to secure them together.

Another object of my invention is to provide an improved substantially all-tubular metallic D-top.

Another object of my invention is to provide an improved D-top as particularly herein later more fully described and claimed.

Other objects of my invention and the invention itself will become apparent from the following description of an embodiment

thereof, and which is illustrated in the accompanying drawings.

Referring to the drawings:

Fig. 1 is a front elevational view of a D-top embodying my invention. 55

Fig. 2 is a side elevational view of the D-top of Fig. 1;

Fig. 3 is an elevational view of one of the two metallic halves of the D-top of Figs. 1 and 2 taken approximately from the plane 60 3 of Fig. 2 and with a wood handle which I employ omitted and drawn to a smaller scale.

Fig. 4 is a view taken approximately from the plane 4 of Fig. 2 with the wood handle 65 omitted;

Figs. 5 and 6 are fragmentary elevational views taken respectively from the planes 5 and 6 of Fig. 3 but drawn to the same scale as Figs. 1, 2 and 4; 70

Fig. 7 is a cross-sectional view taken approximately from the plane 7 of Fig. 1 and with parts beyond the section plane omitted for simplicity.

Referring now to the drawings illustrating a D-top of improved construction embodying my invention, in all of which like parts are designated by like reference characters, at 1 I show one of a pair of complementary sheet metal stampings which are 80 adapted to be placed face to face to form a tubular stale-socket with a pair of hand grip supporting tubular arms extending divergently from the stale-socket. 75

The stamping comprises a stem portion 85 2 of nearly semi-cylindrical channel form and a pair of divergently extending arms 3 and 4, likewise of channel form, being substantially U-shaped in all transverse sections, excepting the end portions. 90

The inner side walls of the arm channels 3 and 4 are joined by an integral web 5, which at the same time forms an end wall for the channeled stem 2. The D-top is given a tubular form by placing together the complementary pair of channeled stampings, each formed as shown at 1, with the edges of the channel side walls of the stem, divergent arms, and web, of the one stamping, brought into contiguous opposed relation to like edges 95 100

of the other stamping, as illustrated in Fig. 1.

In the above described relation, the channeled walls of the one stamping substantially serves as a closure for the channel of the other stamping, to provide substantially tubular construction involving a tubular stale-socket formed by the complementary stem elements 2 and divergent hand grip supporting substantially tubular arms formed by the complementary stamping channels 3 and 4.

The ends of the arms 3 and 4 for each of the stampings are suitably formed so that when the two stampings are brought together, an interlocking relation between the stampings at the arm ends is accomplished in such a way as to hold the stampings together by their arm ends, and to provide for the holding of a hand grip 6 between the ends of the tubular arms formed.

The grip supporting ends 9 and 10 of the arms 3 and 4, respectively, for each stamping, are approximately in the form of discs integrally joined by a peripheral portion 11 to the outer walls 7 and 7' of the channeled arms 3 and 4, respectively. The disc-shaped ends are each centrally perforated for the reception of a grip supporting bolt 8 passed through the disc ends for the two stampings 30 and the longitudinal bore of the grip, in the usual manner.

The complementary pair of stampings are brought together with their channel edges defining a seam 12, which preferably may be widened at 13 in the stale-socket, and adjacent arm portions, the seam extending longitudinally and medially of the handle throughout its width.

The seam may be widened at 13 in order that the tubular stale-socket having the widened seam may accommodate various sized handle ends of a handle such as 14 projected therein and clamped therebetween by bolts 15 projected through perforations 17 of the D-top halves, and through the handle shank 14, telescoped within the stale-socket.

Ordinarily unitary D-tops for implement handles are manufactured complete ready for attachment to the implement handles 50 and are often subsequently shipped to implement factories for attachment to implements, and in order best to fit these in the D-top arm described, without requiring a disassembly and reassembly of the complementary D-top parts, as above described, independently of the implement handle 14, and independently of the grip 6, by securing the disc-like ends of the arms 3 and 4 of the two complementary parts rigidly together ready for use.

In order to accomplish this, the disc-like end 10 of the arm 4 is formed with flange side walls 11' to form a cap for the reception of the disc-like end 9 of the complementary stamping.

The disc end 9 of the channeled arm 3 is abruptly off-set as at 18 relative to the adjacent outer wall 7 of the channel, whereas the disc shaped wall of the arm end 10 is disposed substantially in alignment with the outer wall 7' of the channel arm 4.

In assembling the two halves of the D-top together, therefore, the disc-like end 9 of the one stamping is nested within the flange side walls 11' of the end 10 of the other stamping and vice versa, as shown in Fig. 4. Also, as shown in Fig. 4, the flange side wall 11' projects over and beyond the disc-like end 9 as at 18 and thus provides a pocket into which the end of the grip 6 may be seated.

Cooperative with the pocket 21 thus provided, the inner walls 19 of the arms 3 and 4 adjacent the ends 9 and 10 are cut away as at 20 to fit around the curved surface of the grip 6. Thus, at each end of the grip 6, the ends 9 and 10 are interlocked together.

By means of the off-set 18, the outer walls 7 and 7' of the two channels are brought into substantially planar alignment although the off-set disc end 9 is projected inwardly within the flanged disc end 10 of the other arm.

To prevent rotation of the grip 6 on the bolt 8, the disc ends 9 are preferably provided with relatively sharp inwardly directed projections 22 which project into the wood material of the grip.

The D-top illustrated and described comprises tubular side walls which are sufficiently closed as to prevent objectionable ingress of dirt and moisture. The tubular arms have peripheral walls throughout their lengths from the point where they join the stale-socket to the grip supporting portions 9 and 10, which, as described, are of disc-form to conform to the shape of the grip ends.

The grip ends being received within the flange side walls 11', the grip is given a finished appearance and all portions of the D-top, particularly the grip portions which come into contact with the user's hands, are free of rough edges.

The widened seam 13 between opposing edges of the two stampings effects a resiliently compressible stale-socket.

When the socket is telescoped over the end of a handle and bolts 15 projected through the complementary stale-socket halves, and the drilled handle 14, and the bolts 8 headed over on both sides, the stale-socket halves are drawn down very tightly together against the resiliency of the resilient material forming the substantially tubular D-top, the lower portions of which are adapted to resiliently fulcrum on the shoulders 24 of the joined complementary D-top halves.

Having thus described my invention in a particular embodiment, I am aware that numerous and extensive departures may be made from the embodiment herein illustrated.

and described, but without departing from the spirit of my invention.

I claim:

1. In a **D**-top, the combination of two bifurcated channeled elements adapted to be disposed in opposition, edge to edge, to define a substantially tubular stale-socket and a pair of divergent communicating tubular arms extending therefrom, each element arm 10 provided with a projecting integral end portion, one said end portion of each element en-folding the other end portion of the other element.

2. In a **D**-top, the combination of two bifurcated channeled elements adapted to be disposed in opposition, edge to edge, to define a substantially tubular stale-socket and a pair of divergent tubular arms extending therefrom, an end of each element arm en-folding an end of an arm of the other element, the enfolded end being inwardly offset relative to contiguous portions of its supporting arm.

3. A sheet metal **D**-top including a pair of complementary stampings of generally **Y**-form each channeled on one face to form a nearly semi-cylindrical stale-socket stem portion, and a pair of channeled arm portions extending divergently therefrom, said stampings adapted to be placed face to face, means formed integral with said stampings adapted to secure the stampings together by their arm portions when the stampings are disposed to form a handle-receiving stale-socket and tubular grip supportable arms, and means to tightly clamp said stale-socket portions inwardly against the end of an implement handle projecting therebetween.

4. A sheet metal **D**-top including a pair of complementary stampings of generally **Y**-form each channeled on one face to form a nearly semi-cylindrical stale-socket stem portion, and a pair of channeled arm portions extending divergently therefrom, said stampings adapted to be placed face to face, and means comprising interlocking portions of the arms adapted to secure the arms together when the stampings are disposed to form a handle-receiving stale-socket, and tubular grip supportable arms.

5. A **D**-top comprising a pair of complementary bifurcated substantially **Y**-shaped elements each having a channeled stem and integral channeled arms extending divergently therefrom, said stems adapted to receive an end of an implement shank projected therebetween, and means comprising interlocking portions of complementary arms of said elements to secure the elements 60 together, at the ends of the arms.

6. A sheet metal **D**-top including a pair of complementary stampings of generally **Y**-form each channeled on one face to form a nearly semi-cylindrical stale-socket stem portion, and a pair of channeled arm portions

extending divergently therefrom, said stampings adapted to be placed face to face to form a bifurcated tube, each channeled arm terminating in a substantially flat sheet metal plate integrally formed therewith, and adapted for disposition at an end of a hand grip interconnecting the arms, two of said plates of different stampings being disposed at each end of the hand grip in superposed relation, and a bolt projecting longitudinally through the grip, joining at least two of said plates disposed on opposite ends of the grip.

7. In a **D**-top, the combination of two bifurcated channeled elements adapted to be disposed in opposition, edge to edge, to define a substantially tubular stale-socket and a pair of divergent communicating tubular arms extending therefrom, each element arm provided with a projecting integral end portion, a said end portion for each arm having inwardly directed flanges, each adapted to receive one of the other of said end portions, and a bored hand grip for circular ends disposed in abutting relation between the said received end portions, and bolt means to securely clamp the said end portions against the ends of said grip.

8. In a **D**-top, the combination of two like bifurcated channeled elements adapted to be brought together in opposed relation to define a substantially tubular stale-socket and a pair of divergent tubular arms extending therefrom, the arms for each element both terminating in integrally laterally extending plates adapted to embrace the ends of a hand grip placed between the plate ends of the arms, the plates being disposed in parallel planes, the plates of the two elements at each end of the grip being in superposed relation.

9. A sheet metal **D**-top including a pair of complementary stampings of generally **Y**-form each channeled on one face to form a nearly semi-cylindrical stale socket stem portion, and a pair of channeled arm portions extending divergently therefrom, said stampings adapted to be placed in opposition edge to edge, each arm portion at its end overlapping a part of the opposite arm.

10. A sheet metal **D**-top including a pair of complementary stampings of generally **Y**-form each channeled on one face to form a nearly semi-cylindrical stale socket stem portion, and a pair of channeled arm portions extending divergently therefrom, said stampings adapted to be placed in opposition edge to edge, each arm portion at its end overlapping a part of the opposite arm, and formed to interlock them against opposite separation.

11. A sheet metal **D**-top including a pair of complementary stampings of generally **Y**-form each channeled on one face to form a substantially semi-cylindrical stale socket stem portion, and a pair of channeled arm portions extending divergently therefrom,

6 said stampings adapted to be placed in opposition edge to edge, each arm portion overlapping a part of the opposite arm, a hand grip between the pairs of overlapping arm ends, and a bolt extending through a pair of overlapped ends and into the hand grip.

12. A sheet metal D-top including a pair of complementary stampings of generally Y-form each channeled on one face to form a substantially nearly semi-cylindrical stale socket stem portion, and a pair of channeled arm portions extending divergently therefrom, said stampings adapted to be placed face to face in opposition, each arm portion 15 at its end being provided with an integral plate over-lapping a corresponding plate of the opposite arm end, a hand grip extending between the pairs of overlapped plates, the plates being provided with aligned perforations and a bolt extending through a pair of 20 perforations of the plates and into the hand grip.

13. A sheet metal D-top including a pair of complementary stampings of generally Y-form each channeled on one face to form a nearly semi-cylindrical stale socket stem portion, and a pair of channeled arm portions extending divergently therefrom, said stampings adapted to be placed face to face in opposition, each arm portion at its end being provided with an integral plate overlapping a corresponding plate of the opposite arm end, one of the plates of each pair being provided with a perimetral flange overlapping 35 the perimeter of the other plate of the pair to interlock the plates against opposite separation.

14. A sheet metal D-top including a pair of complementary stampings of generally Y-form each channeled on one face to form a nearly semi-cylindrical stale socket stem portion, and a pair of channeled arm portions extending divergently therefrom, said stampings adapted to be placed face to face in opposition, each arm portion at its end being provided with an integral plate overlapping a corresponding plate of the opposite arm end, one of the plates of each pair being provided with a perimetral flange overlapping 45 the perimeter of the other plate of the pair to interlock the plates against opposite separation, a hand grip extending between the pairs of overlapped plates and the said flanges overlapping the ends of the hand grip.

55 15. A sheet metal D-top including a pair of complementary stampings of generally Y-form each channeled on one face to form a nearly semi-cylindrical stale socket stem portion, and a pair of channeled arm portions 60 extending divergently therefrom, said stampings adapted to be placed in opposition edge to edge, each arm portion overlapping a part of the opposite arm, and formed to interlock them against opposite separation.

65 16. A sheet metal D-top including a pair

of complementary stampings of generally Y-form each channeled on one face to form a substantially nearly semi-cylindrical stale socket stem portion, and a pair of channeled arm portions extending divergently therefrom, said stampings adapted to be placed face to face in opposition, each arm portion at its end being provided with an integral portion overlapping a part of the opposite arm end, a hand grip extending between the pairs of overlapped portions, at least one of the overlapped portions being provided with a 70 perforation and a securing element extending through the perforation into the hand grip.

75 In testimony whereof I hereunto affix my signature this 9th day of September, 1929.

80 WILLIAM H. BERGMANN.
